UNITED STATES PATENT OFFICE.

JOHN B. HOWAT, OF SHARON, PENNSYLVANIA.

DESIGN FOR A HINGE.

Application filed December 30, 1922. Serial No. 4,763. Term of patent 14 years.

To all whom it may concern:

Be it known that I, JOHN B. HOWAT, a citizen of the United States, residing at Sharon, in the county of Mercer and State of Pennsylvania, have invented a new, original, and ornamental Design for a Hinge, of which the following is a specification, reference being had to the accompanying drawing, forming part thereof.

I claim:

The ornamental design for a hinge, as shown.

JOHN B. HOWAT.
